UNITED STATES PATENT OFFICE.

CHARLES E. LINDSEY, OF GREENFIELD, OHIO, ASSIGNOR OF ONE-HALF TO
CHARLES G. HAYES, OF GREENFIELD, OHIO.

BED-BOTTOM.

SPECIFICATION forming part of Letters Patent No. 729,950, dated June 2, 1903.

Application filed June 19, 1902. Serial No. 112,345. (No model.)

To all whom it may concern:

Be it known that I, CHARLES E. LINDSEY, a citizen of the United States, residing at Greenfield, in the county of Highland and State of Ohio, have invented certain new and useful Improvements in Bed-Bottoms, of which the following is a specification.

This invention relates to bed-bottoms, and has for its object to provide a device of this character which will combine the advantages of slats and springs, whereby the bed-bottom as a whole is adapted to yield under the weight of the occupant and at the same time will remain level and not tend to sag, as is the case with spring bed-bottoms as generally constructed.

A further purpose of the invention is to provide a bed-bottom which can be readily taken apart for convenience of handling, either when moving or for purpose of cleaning, and which can be readily adapted to the weight of the occupant or occupants.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a top plan view of a bedstead embodying the invention. Fig. 2 is an elevation of a portion of a side rail on a larger scale. Fig. 3 is a section about on the line X X of Fig. 2. Fig. 4 is a section about on the line Y Y of Fig. 2.

Corresponding and like parts are referred to in the following description and indicated in all the views of the drawings by the same reference characters.

The invention is applicable to a bedstead of any design, make, or construction, and appertains more particularly to the bed-bottom or means for supporting the slat-rests. The bedstead shown is of ordinary construction and comprises the head-piece 1, foot-piece 2, and side rails 3, the several parts being connected in the usual manner, so as to admit

of the bedstead being readily taken apart for any desired purpose.

The slat-rests 4 are provided in their upper edges with gains 5 for reception of the slats 6, said rests 4 in the present instance being yieldingly connected with the proximal side rails 3, preferably by means of springs 7, which are attached at their upper ends to the respective side rails 3 and at their lower ends to the respective slat-rests 4. The springs 7 are of the coil type and may be attached to the parts 3 and 4 in any desired way and may be provided in any number and spaced apart any distance. The lower ends of the springs 6 have detachable connection with the slat-rests 4 to admit of throwing one or more of the springs out of action when it is desired to loosen the spring tension, so as to admit of the bed-bottom yielding to the weight of a child or light person. This construction also admits of having the slat-rests supported by different spring tension, which is of advantage when the occupants of the bed are of different weight, so as to preserve the bed-bottom in a level position. The slat-rest upon the side of the bed designed to support the heavier weight may be supported by all of the springs, whereas the slat-rest on the side of the bed for supporting a lighter weight may be connected to the side rail by a less number of springs, thereby permitting the bed-bottom to move and at the same time remain parallel to a given position, although supporting a load of unequal weight at each side. The springs may be connected at their lower ends to the slat-rests in any way so long as provision is had for their ready disconnection and attachment as may be required. As shown, the upper ends of the springs are formed with eyes, 8, which are looped into screw-eyes 8, let into the side rails, and their lower ends are formed with hooks 9 to engage corresponding hooks 10, applied to the slat-rests.

To prevent end and lateral play of the slat-rests, guides are provided between them and the side rails and may be of any construction. As shown, rods 11 are applied to the side rails near each end and engage eyes 12 at the sides of the slat-rests. The eyes 12 or the rods 11 may be lined with rubber or other material, so as to prevent rattle or noise when

the bed-bottom moves under the weight or shifting of the occupant. The rods 11 are preferably of L form and have their lower ends secured to the side rails in any substantial manner, the upper ends being free, so as to admit of the slat-rests being readily removed to admit of access to the parts for repairs, cleaning, or other purpose.

Within the spirit of the invention any well-known form of spring may be substituted for the part 7 so long as it serves to yieldingly connect the slat-rest with the bedstead.

Having thus described the invention, what is claimed as new is—

- 15 1. In a bed, the combination with the rails, bed-bottom and suspending-springs between the rails and bed-bottom, vertical guides attached at their lower ends to the said rails and spaced therefrom at their upper ends,
- 20 2. and eyes attached to the bed-bottom and co-operating with the said guides to direct the bed-bottom in its vertical movements, limit its downward motion and admit of lifting it from the guides when required to remove the bed-bottom for any purpose, substantially as specified.
- 25

2. In a bed, the combination with the side rails and slat-rests parallel with and spaced from the side rails, springs located in the space formed between the adjacent rails and 30 slat-rests and protected thereby and having their upper ends attached to the top portion of the rails, means detachably connecting the lower ends of the springs with the bottom portion of the slat-rests to admit of throwing 35 one or more springs out of action, vertical guides attached at their lower ends to the said rails and spaced therefrom at their upper ends, and eyes attached to the bed-bottom and co-operating with the said guides to direct the bed-bottom in its vertical movements, limit its downward motion and admit of lifting it from the guides when required to remove the bed-bottom for any purpose, substantially as specified. 40

In testimony whereof I affix my signature in presence of two witnesses.

CHARLES E. LINDSEY. [L. S.]
